UNITED STATES PATENT OFFICE.

SIGMUND LEDERER, OF PROVIDENCE, RHODE ISLAND.

DESIGN FOR A WATCH-BRACELET.

59,972.

Specification for Design.

Patented Dec. 13, 1921.

Application filed September 6, 1921. Serial No. 498,923. Term of patent 14 years.

To all whom it may concern:

Be it known that I, SIGMUND LEDERER, a citizen of the United States, residing at Providence, in the county of Providence and State of Rhode Island, have invented a new, original, and ornamental Design for a Watch-Bracelet, of which the following is a specification, reference being had to the accompanying drawings, forming part thereof.

I claim:

The ornamental design for a watch bracelet, as shown.

SIGMUND LEDERER.
